UNITED STATES PATENT OFFICE.

CHARLES F. MOSMAN, OF BRIDGEPORT, CONNECTICUT, ASSIGNOR TO THE JENNINGS BROS. MANUFACTURING COMPANY, OF SAME PLACE.

DESIGN FOR A CLOCK-CASE.

SPECIFICATION forming part of Design No. 33,279, dated October 2, 1900.

Application filed July 30, 1900. Serial No. 25,361. Term of patent 7 years.

To all whom it may concern:

Be it known that I, CHARLES F. MOSMAN, a citizen of the United States, and a resident of Bridgeport, in the county of Fairfield and State of Connecticut, have invented and produced a certain new and original Design for Clock-Cases, of which the following is a specification, reference being had to the accompanying drawings, forming a part thereof.

10 Figure 1 is a front elevation of the clock-case embodying my new design. Fig. 2 is a side view of Fig. 1.

As shown in the illustrations, the leading or material features of my design consist in 15 an ornamented clock-case, substantially as herein shown and as now will be described in detail.

The opening A for the movement is centrally located and is ornamented by a plain 20 convex ring B, as shown. A pair of ribs C extend around the lower edge of the base of the case, and adjoining these ribs is a concave belt D, having a third rib E bordering its upper edge. A raised shield F is arranged with 25 in an enlargement of the belt at the front and back sides of the case, and a raised leaf G is shown upon either side of said shield and within the belt. The four corners of the case are ornamented in scroll, leaf, and bead effect 30 H, I, and J, respectively, presenting a graceful concave-convex outline. Central of the

sides of the case is a raised oval panel K, having a scroll and beaded border, the treatment of which is in harmony with the adjoining corner ornamentations. Upon each of these 35 panels and corner ornamentations is a transverse convex rib L, forming two plain outer and two carved inner sections. The top of the case contains a central transverse rope decoration M, with a pair of artistic leaves N 40 on either side. The upper portion of the front and back of the case, like the side, is shown ornamented in scroll-and-leaf effect and comprises a pair of large scrolls O, extending from the center of the top to the outer edges, and 45 the same having a series of smaller scroll-and-leaf ornamentation upon either side thereof. A handsome handle P is attached to the top of the case and, like the rest of the design, is artistically decorated in leaf, scroll, and bead 50 relief.

Having thus described my invention, what I claim, and desire to secure by Letters Patent, is—

The design for a clock-case, as herein shown 55 and described.

Signed at Bridgeport, Fairfield county, Connecticut, this 24th day of July, A. D. 1900.

CHARLES F. MOSMAN.
